(57) **CLAIM**

The ornamental design for a rotational snap action clamp, as shown and described.

DESCRIPTION

FIG. 1 is a rear and side elevational perspective view of one side of a rotational snap action clamp;

FIG. 2 is a rear and side elevational perspective view of the opposite side of a rotational snap action clamp;

FIG. 3 is a top view of a rotational snap action clamp;

FIG. 4 is a bottom view of a rotational snap action clamp;

FIG. 5 is a front elevational view of a rotational snap action clamp;

FIG. 6 is a rear elevational view of a rotational snap action clamp;

FIG. 7 is a side elevational view of one side of a rotational snap action clamp; and,

FIG. 8 is a side elevational view of the opposite side of a rotational snap action clamp.

The broken line showing of an attachment rod in FIGS. 1 and 2, and a visual fixation device attached to the rotational snap action clamp in FIGS. 1, 2, 3, 4, 7 and 8, is for illustrative purposes only, and forms no part of the claimed design.
